UNITED STATES PATENT OFFICE.

PATRICK McDONOUGH, OF DOVER, NEW HAMPSHIRE.

ARTIST'S CANVAS-HOLDER.

SPECIFICATION forming part of Letters Patent No. 634,064, dated October 3, 1899.

Application filed January 23, 1899. Serial No. 703,143. (No model.)

To all whom it may concern:

Be it known that I, PATRICK McDONOUGH, a citizen of the United States, residing at Dover, in the county of Strafford and State of New Hampshire, have invented a new and useful Improvement in Artists' Canvas-Holders, of which the following is a specification.

This invention is a canvas-holder for artists' use, the object being to provide a simple and convenient appliance which can be arranged within the cover of the color-kit for the purpose of holding the canvas before the paint is thoroughly dry.

Another object of the invention is to construct the device so that it will be readily adjustable to accommodate different sizes of frames; and with these objects in view my invention consists, essentially, of grooved guideways adapted to be arranged upon the interior of the box-cover, said ways crossing each other at the center, and headed bolts sliding in said ways and carrying a washer and thumb-nut upon the threaded end for the purpose of binding the corner of the canvas to the guideway.

The invention consists also in certain details of construction and novelties of combination, all of which will be fully described hereinafter and pointed out in the claims.

In the drawings forming part of this specification, Figure 1 is a view showing the practical application of my invention. Fig. 2 is a perspective view of the guideways, showing the manner of crossing or intersecting each other, the fastening-bolt being shown in dotted lines. Fig. 3 is a detail view showing the guideway in section, the fastening-bolt and the frame carrying the canvas being shown in elevation.

In the practical embodiment of my invention I employ the grooved guideways A, which are secured to the inner face of the top or cover of the paint-box, said ways extending diagonally across said top, as shown, and intersecting each other at the center, and where the said guideways intersect each other the slotway is cut out, as shown at A', in order to permit the insertion of the head B of the bolt C, which slides back and forth in the slot of the guideways, there being four such bolts at the center and sliding into its respective slot, it being understood, of course, that each bolt is intended to slide back and forth

in its respective slot to or from its respective corner, all of the slots having a common center. Each bolt carries a washer D sufficiently large to overlap the corner of the frame E, said frame resting upon two lower bolts, while the two upper bolts fasten the upper edges, the washer D being made to overlap the corners and are securely fastened by means of the winged nuts F, screwed upon the ends of the bolts D.

It will be seen that the grooves after being made to overlap the corners are securely fastened upon the inside of the top and the top closed without affecting the painting, as it will be held out of contact with any other object.

If desired, the invention can be employed for the purpose of holding canvas while it is being painted upon, thereby dispensing with the use of an easel or rack. The guideways can be made of wood or metal and secured to the cover in any suitable manner, and they can be made in one piece or a number of pieces, as desired, so long as a series of guideways are provided having a common center in which the fastening-bolts can be adjusted for the purpose of securing the frame carrying the canvas.

Having thus fully described my invention, what I claim as new, and desire to secure by Letters Patent of the United States, is—

1. In a device of the kind described, the combination with a suitable box, of a canvas-holder comprising the slotted guideways secured upon the inner side of the top or cover, said guideways intersecting each other at the center, the way being enlarged at said central intersection, headed bolts adapted to slide in the said guideways, the washer and the winged nuts all arranged substantially as described.

2. The combination with a suitable box having a cover or lid of a canvas-holder secured upon the inner side of said cover comprising slotted guideways extending diagonally across said cover and intersecting each other at the center, said central portion being enlarged for the reception of headed bolts, substantially as described.

PATRICK McDONOUGH.
